United States Patent Office

Des. 212,536
Patented Oct. 29, 1968

212,536

CABINET FOR AN ELECTRONIC DEVICE OR SIMILAR ARTICLE

Harvey E. Diamond, Brooklyn, N.Y., assignor to Union
Broach Co., Inc., Long Island City, N.Y., a corporation
of New York

Filed Jan. 30, 1968, Ser. No. 10,358

Term of patent 14 years

(Cl. D26—5)

FIG. 1

FIG. 2

FIG. 1 is a right front perspective view of a cabinet for an electronic device or similar article, embodying my new design; and

FIG. 2 is a left rear perspective view thereof.

The dominant features of the design reside in the portions shown in full lines.

I claim:

The ornamental design for a cabinet for an electronic device or similar article, as shown and described.
